CLAIM

The ornamental design for a jewelry item, as shown and described.

DESCRIPTION

FIG. 1 is a front perspective view of a jewelry item showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken line showings on the front and back of the jewelry item illustrate optional elements that form no part of the claimed design. The broken line showing of the bail on top of the jewelry item is for environmental purposes only and forms no part of the claimed design.
